EX

DE 374

OR D 12,355

Design No. 12,355, dated July 12, 1881.

UNITED STATES PATENT OFFICE.

GEORGE H. HUGHES, OF NEW YORK, N. Y.

DESIGN FOR ENAMELED AND TABLE OIL-CLOTH.

SPECIFICATION forming part of Design No. 12,355, dated July 12, 1881.

Application filed May 25, 1881. Term of patent 3½ years.

To all whom it may concern:

Be it known that I, G. H. HUGHES, a citizen of the United States, residing in the city of New York, State of New York, have invented 5 a certain new and useful Design for Enameled and Table Oil-Cloth, fully described and represented in the following specification and the accompanying fac-simile, forming a part of the same.

10 The design illustrated is a combination of eight-sided figures and squares, the octagonal figures touching one another upon alternate sides, and the intermediate sides forming the boundaries of the squares. The figures are 15 represented in the fac-simile as formed by white lines upon a black ground, and the squares and octagons are all surrounded by a narrow white line, separated slightly from the boundary-line of the adjacent figure. In 20 the center of each octagon is a rosette-shaped figure, from which eight lines radiate to the boundary-line of a sixteen-sided figure arranged inside each octagon, and covering nearly one-half of its area. In each alternate 25 octagon the sixteen sides are disposed to form an eight-pointed star of obtuse angles, with eight white lines extending from its inner angles to the rosette in the center. In the intermediate octagons the sixteen sides are of equal 30 ogee shape, forming eight points extending outward and eight points inward, with eight dark lines extending from the inner points to the rosette. In the spaces between the eight dark lines are eight *fleur-de-lis*; and in the 35 alternate octagons, between the eight white lines, are eight small rosettes of eight loops each. Around the sixteen-sided figures are disposed eight figures containing the small eight-looped rosettes in the center and having 40 eight-looped *fleur-de-lis* in contact with it upon two sides. In the middle of the line dividing each two adjoining octagons is a rosette, from which

several parallel lines run to the nearest point of the sixteen-sided figures. Each square is about one-fourth the area of the octagons, 45 which form the prominent feature of the design, and is nearly filled by a Greek cross, having its surface ornamented with an open Gre- 50 cian pattern. The corners of the square are filled with fine tracery, and the ground of the square and of a portion of the octagons, as shown, is also formed of a fine network pattern which scarcely shows in contrast with the figures upon it.

Having thus described the design, I do not 55 wish to limit myself to the exclusive employ- 60 ment of white lines upon a black ground to produce the same, as it is the shape of the figures which I claim, and not the colors in which they may be represented.

The tracery described for the background in 65 certain of the figures is not an essential fea- 70 ture of my design, nor the precise shape of the finer ornamental details, and I do not limit myself to their use.

The above design may, if desired, be formed of several harmonious colors, or of any dark or light color impressed upon a contrasting background.

The design may be used to cover the entire 70 surface of the enameled cloth, or for its middle, in combination with a suitable border, or otherwise employed upon the class of goods described.

I therefore claim—

The design for table and enameled oil-cloth, 75 substantially as herein shown and described.

In testimony whereof I have hereunto set my hand in the presence of two subscribing wit- 80 nesses.

GEORGE H. HUGHES.

Witnesses:

HENRY G. GURNEY,
J. HAGUE ARMITAGE.
